UNITED STATES PATENT OFFICE.

FREDERICK CAPEL BROWN, OF WAIHI, NEW ZEALAND.

LINING FOR TUBE-MILLS AND BALL-MILLS.

991,421.

Specification of Letters Patent. Patented May 2, 1911.

Application filed April 15, 1908. Serial No. 427,269.

To all whom it may concern:

Be it known that I, FREDERICK CAPEL BROWN, a subject of His Majesty the King of the United Kingdom of Great Britain and Ireland, resident of Waihi, in the provincial district of Auckland and Dominion of New Zealand, mine superintendent, have invented an Improved Lining for Tube-Mills and Ball-Mills and Similar Grinding and 10 Pulverizing Machines, of which the following is a specification.

This invention relates to new and useful improvements in ball mills for pulverizing material by trituration wherein the mill cylinder is lined internally with slabs having longitudinally ribbed working faces.

One object of the invention is to improve the liner construction by forming the ribs thereof with working faces inclined inwardly in the direction of rotation of the mill, in order that the cascading action of the balls may be rendered more efficient.

A further object of the invention is the provision of a liner consisting of a series of 25 metal slabs which are each of such construction that the efficient life of the liner is greatly prolonged, this advantage resulting from the fact that each slab is of increased thickness throughout a longitudinal central 30 portion, which portion is of greater thickness than the portions of the slab on either side thereof, is equidistant from the side edges of the slabs and from the seams or joints coincident with said side edges, is 35 subject to greater wear than the other portions of the slab and has greater wear resisting property. The slabs are themselves readily renewable and are preferably of a construction which provides for the ready 40 renewal of parts or sections thereof.

Embodiments of the invention are illustrated by way of example in the accompanying drawings, wherein—

Figure 1 is an elevation of an end of the 45 tube mill, showing the manner in which the slabs and their adjuncts are fitted therein; Fig. 2 is a plan view of one of the slabs showing more particularly the central reinforcing bar thereon, and the recesses in the 50 edges of the slab which partially surround the securing bolts; Fig. 3 is a plan view of a bar of iron or other suitable material, which is constructed with enlargements at suitable intervals for a purpose to be described; Fig. 4 is a cross sectional view of

the bar shown in Fig. 3; Fig. 5 is a cross sectional view of a modified form of bar, intended for the same purpose as the bar shown in Fig. 3; Fig. 6 is an enlarged cross sectional view of one form of slab construction; Fig. 7 is a cross sectional view of an alternative slab construction; and Fig. 8 is a cross sectional view of a further alternative slab construction.

Similar characters of reference designate 65 corresponding parts throughout the several views.

Referring to Fig. 1, which shows essentially the manner in which the slabs are fastened, the letter A designates a tube or similar mill which is fitted with slabs extending longitudinally thereof. These slabs are constructed with central longitudinal portions of increased thickness, for a purpose which will presently appear. In the arrangement 70 shown in Fig. 1, the slabs designated by the numeral 1, each have a central longitudinal rib, as 2, upon which is removably fitted a wear bar, as 3, the working faces of the slabs on each side of the rib being flat. The 75 bar 3 has its working face inclined inwardly in the direction of rotation of the mill, as is indicated by the arrow B, and its use upon the rib 2, though preferred, is optional. The wear bar 3 has an L-shaped cross section, in 80 order that it may be more readily and accurately centered upon the rib to which it is fitted, the flange of said wear bar fitting against a side face of the rib and the body portion of said wear bar entirely covering 85 the plan face of the rib.

Fig. 6 is an enlarged cross sectional view of the particular form of slab shown in Fig. 1, as applied to the mill cylinder.

Referring to Fig. 7, wherein an alternative form of slab is illustrated, the central rib shown in Figs. 1 and 6, is not employed. Instead of using this construction, the thickness of the slab is gradually increased from each of its longitudinal side edges or from lines inwardly thereof, to a median line at which the greatest wear occurs, oppositely and inwardly inclined wearing faces, as 5, and a central longitudinal apex, as 6, being thus afforded. The alternative form of 100 slab shown in Fig. 8, is of uniform thickness except at its central portion where a central longitudinal rib, as 7, is provided.

All the forms of slabs above referred to, may be provided along their side edges at 110

suitable intervals with recesses or half-holes, as 8, the recesses 8 of one slab registering with the correspondingly located recesses of an adjacent slab. The fastening 5 bolts by which the slabs are connected to the cylindrical body of the mill, may be passed through these recesses, as indicated in Fig. 1. In connection with the fastening of the slabs, it is preferred to employ longitudinal 10 bars, as 10, which not only are of advantage in providing for a more efficient fastening of the slabs but also may serve as cascading bars, in which function they correspond to the central longitudinal ribs above referred 15 to. In Figs. 3 and 4, the bar 10 is shown as of solid construction and is provided at intervals with openings, as 11, through which the fastening bolts 12, connecting the slabs and the mill cylinder, pass. Adjacent 20 the openings 11, the bar 10 may, if desired, be provided with enlargements, as 13, by reason of which the provision of the openings 11 will not weaken the bar.

Instead of making the bars 10 of solid 25 construction, as shown in Fig. 4, I may make them of sectional construction, as shown in Figs. 1 and 5, in which case the bar comprising a body section as 10^a and a wear bar section, as 14, which is fitted upon the inner 30 face of the body section and is held by the securing bolts 12. The bar 14 corresponds in function to the wear bars 3 above referred to, and, like the latter, is readily renewable. In Fig. 5, the wear bar 14 is shown as having 35 a flat wearing face whereas in Fig. 1 the wear bar 14 is shown as having an inclined wearing face, and similar in all respects to the bars 3 shown in the same figure. The inclined wearing faces are preferred, though 40 if circumstances or conditions of use should render it desirable, the bars 3 or 14 may be formed with flat working faces. If for any reason, the use of either of the wear bars is not desired, the faces of the ribs or bars 10 45 as the case may be will then become working faces and may be made flat or inclined, in the manner stated. It will also be understood that wear bars may be applied to the ribs of the slabs shown in Figs. 7 and 8, if 50 desired.

To provide for the ready assemblage of the renewable wear bars, the latter are preferably of an L-shaped cross section, whereby they may be readily centered upon a rib.

55 By forming the slabs with central portions of increased thickness, that wear at the joints or edges of the slabs which is inherent in a number of prior arrangements and to overcome which special constructions 60 have been proposed, is eliminated or minimized to a great extent, since the balls bound against the central portions. It requires a considerable period of time for the balls to wear down the reinforced central portions 65 and in the meantime the slab is not broken

or otherwise rendered useless. It is thus assured that the slab shall have an efficient life consistent with its greatest thickness. The arrangement is also of advantage in that it provides for the utilization of the 70 fastening bars in the manner and for the purposes described. Where the renewable wear bars are used, the life of the liner may be prolonged until the slabs are worn so thin as to be wholly unfit for further use. 75

It will be found by this invention that the lining of a mill can be put in quickly and securely and that renewals can be easily made; that the fastening bars besides holding the slabs securely in position, have the 80 further advantage of preventing undue wear caused by the sliding motion of the pebbles or balls on the lining of the mill; that by inclining the faces of these bars in the manner indicated, the pebbles or balls are lifted 85 higher at each revolution of the mill, thus increasing the grinding or pulverizing efficiency of the mill; and that by reason of the thickness of the slabs being proportioned as described, the loss of metal and worn-out 90 liners, is reduced. This method of running a mill improves the work done by the mill by preventing the slipping of the pebbles or balls on the lining of the mill and the grinding efficiency of the mill is increased, due to 95 the lifting action of the bars on the pebbles or balls. Economy is also maintained by this action in the wear of the liners.

The slabs and other parts are shown as only fitted within a portion of the inside of 100 the mill, but in practice they will preferably be fitted all around the inside and their form may be varied according to circumstances.

Having fully described my invention what I desire to claim and secure by Letters Patent is:—

1. A tube mill liner comprising a series of longitudinally disposed slabs removably assembled in the mill structure and having longitudinal central portions of increased 110 thickness, and wear bars secured to said central portions and projecting inwardly with respect to the mill.

2. A tube mill liner comprising a series of longitudinally arranged slabs removably 115 assembled in the mill and having longitudinal central portions of increased thickness, and longitudinally disposed wear bars arranged on said central portions and having their working faces transversely inclined in 120 the direction of rotation of the mill.

3. A tube mill liner comprising a plurality of longitudinally assembled slabs, attachment bars overlapping the adjacent slabs and projecting inwardly with respect 125 thereto, means for attaching the bars to the mill structure, wear bars removably secured to the said attachment bars and extending longitudinally centrally disposed thereof, said slabs having longitudinal wear ribs in- 130

tegral therewith and bars removably attached to said ribs and extending longitudinally thereof.

4. A tube mill liner comprising a series of removably fitted longitudinally disposed metal slabs, each of which has its longitudinal central portion of greater thickness than the portions on either side thereof, in combination with longitudinal inwardly projecting bars removably secured in the mill along lines midway between the central portions of adjacent slabs.

5. A tube mill liner comprising a series of longitudinally disposed metal slabs, each of which has its longitudinal central portion of greater thickness than the portions on either side thereof, in combination with longitudinal inwardly projecting fastening bars overlying portions of the slabs on each side thereof.

6. A tube mill liner comprising a series of longitudinally disposed metal slabs each of which has its longitudinal central portion of greater thickness than the portions on either side thereof, in combination with longitudinal inwardly projecting bars removably secured in the mill along lines midway be-

tween the central portions of adjacent slabs and longitudinally disposed wear bars fitted upon said first named bars.

7. A tube mill liner comprising a series of longitudinally disposed metal slabs, each of which has its longitudinal central portion of greater thickness than the portions on either side thereof, in combination with longitudinal inwardly projecting fastening bars overlying portions of the slabs on each side thereof and longitudinally disposed wear bars removably fitted to said fastening bars.

8. A tube mill liner comprising a series of removably fitted longitudinally disposed metal slabs assembled to provide an imperforate interior tube mill working surface, the slabs being characterized by longitudinally and centrally disposed inwardly extending spaced ribs which have their working faces transversely and inwardly inclined with respect to the direction of rotation of the mill.
